J. H. REEDY ET AL

SUCTION BOX

Filed April 7, 1925

UNITED STATES PATENT OFFICE.

JOHN H. REEDY AND THOMAS A. CAPE, OF HAMILTON, OHIO, ASSIGNEES TO THE CHAMPION COATED PAPER COMPANY, OF HAMILTON, OHIO, A CORPORATION OF OHIO.

SUCTION BOX.

Application filed April 7, 1925. Serial No. 21,409.

Our invention relates to suction boxes in general and particularly as required for removing the excess moisture from paper stock in paper making machines such as the well known Fourdrinier type.

In making paper on such a machine it is usual to provide a tank in which the flocculent paper stock is settled in a sheet on a moving screen. The screens used for this purpose are in the form of endless belts which are supported on interspaced rollers. At the inlet end of this endless screen belt the sheet of paper is very wet. As it travels along the belt much of the water drips off, but it aids very materially to provide suction boxes abutting the screen which pull the excess water from the sheet through the screen. It is particularly to improvements in suction boxes for the foregoing purposes that our invention relates.

Provision must be made in the suction box to blank off the unused sides of the screen when a sheet of paper of less width than the maximum width of the screen is to be run. Heretofore it has been customary to provide blanking off members within the suction box which are adjustable from a rod located at the ends of the box. This has never provided a very positive and sure way of blanking off the sides of the suction box so that our invention further relates to improvements in the provision for transverse adjustment of the openings into the suction box.

It is a further object of our invention to provide a suction box which will be light in construction and which will not have any tendency to sag at the middle of the screen and so make an imperfect seal between the box and the screen. It is further our object to construct a suction box which may be easily inserted and withdrawn and which may also be easily cleaned out. The resultant effect of our new box on the paper made is to take water from the sheet more uniformly, to prevent undue streaking of the sheet, and to lengthen the life of the endless screen belt.

These several objects we accomplish by that certain structure hereinafter described and claimed.

In the drawing:

Figure 1 is a side elevation of a suction

box constructed in accordance with our invention.

Figure 2 is a section along the lines 2—2 in Figure 1.

Figure 3 is a section along the lines 3—3 in Figure 1.

Figure 4 is a side elevation taken from the end of the suction box opposite the suction line.

Figure 5 is a perspective view of one form of blanking-off rail for the transverse adjustment of the opening in the box.

Figure 6 is a section corresponding with the section shown in Figure 2 in which a modified form of abutment rail is used, made from an integral piece, and

Figure 7 is a perspective view of a modified form of adjustment rail for the end of the box which may be used in conjunction with the integral abutment rail shown in Figure 6.

Generally indicated at 1 are the walls of the hollow casing or box which are preferably of metal or other rigid material. An aperture 2 forms a suction opening longitudinally of the box. The ends of the box are open for attachment of a suction pipe 1^a at one end and a plate 1^b closes the other end. The upper sides are flanged over at 3 widthways of the box so as to form a platform and upwardly extending dovetails 4 are disposed in the upper face of the flanged portions. In the first form shown wooden strips or rails 5 are provided with cooperating grooves 6 which engage the dovetails so that the wooden strips may be pushed into position on the flanged portions 3 from the ends of the box, leaving the suction aperture between them. The rails are as noted preferably of wood, but it is also possible to construct them of composition material or soft metal, the particular reason for the use of wood is that it may be planed off when it becomes worn and it does not provide a hard bearing structure which would tend to wear out the screen. At each end the rails are recessed as at 6^a and a plate 7 is slidably engaged in the recessed portion and a rail portion 8, mounted on the plate, fills up the opening between the rails 5 so that by pushing these plates toward the center of the box, the ends may be effectively blanked off so

that a sheet of less width than the maximum

which the screen will take may be run and there will be no air leaks at the end to hinder perfect suction within the box withdrawing the moisture from the sheet of paper.

The box is attached to the side frames 9 of the machine by bolts 10 which pass through holes 11 in the flanged end portions 12 of the box. Adjustment bolts 13 or 10 screws are disposed on both sides of the bolts 10 which abut the frame and which may be used to tighten the tension on the bolts 10 when they are set in the desired position.

15 Inasmuch as it is frequently necessary to remove the wooden strips 5 which abut the screen and to plane them off to provide a smooth bearing surface, the supporting flanges 12 at the ends should be below the 20 locking tongues 4 and the whole box should be adjustable from the frame in order to allow for the planing down of the wooden strips.

It will be further noted that the lower 25 corners of the box are formed with longitudinally extended webs 14 formed integrally with the box. These webs materially reinforce the rigidness of the box and prevent sagging in the middle. When it is 30 desired to make a sheet of less width than the maximum suction opening, the end rails 8 are pushed inwardly until the opening in the box is the equivalent of the width of the sheet to be made.

35 The preferred structure of abutment rail is that shown in Figure 6. In this the abutment rail instead of being separate rails is made in an integral piece 15, which has grooves 16 which are engaged in upwardly 40 projecting undercut flanges 17. The portion of the rail opening into the aperture 2 in the casing is provided with holes 18 which will preferably be tapered outwardly at the base. Tapering of these holes avoids the 45 tendency for the holes to become blocked up. The ends of the one piece rail are provided with recessed portions 19 below the level of the top, and truncated wedge-shaped members 20 are slidably retained in the recessed portions. By pushing inwardly on the members 20 transverse adjustment of the 50 opening area into the suction box may be accomplished. The reason that this form of abutment rail is more satisfactory than the 55 separate rails is that there is less tendency to uneven wear and warping, which results in much longer life for the screen.

The suction from the side of the box seems to distribute the suction action more evenly 60 across the screen than the old type of suction box which was made of a hollow tank with a suction pipe threaded into the central part of the bottom. It will be further quite apparent that for cleaning a box made 65 in accordance with our invention, all that

is required is to remove a cap 1^b secured at the end opposite the suction end, and to flush the box out with water. The box top or rails do not in either form of our invention require any nails or bolts to secure them 70 to the casing so that there is no tendency for the rails to chip off and wear as there would be if secured by any form of metal tie.

Having thus described our invention, what 75 we claim as new and desire to secure by Letters Patent, is:—

1. A suction box for paper machines comprising a hollow casing, open at one end for attachment to a suction line, a lengthwise 80 opening in said casing, and slidably mounted screen engaging means protecting said opening, said screen engaging means having slideways at the ends thereof, and passage closing means slideable in said slideways. 85

2. A suction box for paper making machines comprising a hollow casing having lateral flanges forming an integral top, said flanges leaving an opening between them, a suction connection at one end of the casing, 90 and a removable closure for the other end of the casing to permit flushing, and means mounted on the box for protecting a screen passing over said opening.

3. A suction box for paper making ma- 95 chines comprising a hollow casing having lateral flanges forming an integral top, said flanges leaving an opening between them, a suction connection at one end of the casing, and a removable closure for the other end of the casing to permit flushing, and means mounted on the box for protecting a screen 100 passing over said opening, said means comprising a foraminated integral body, and dovetails on the casing flanges for slidably 105 engaging the same.

4. A suction box for paper making machines comprising a hollow tubular casing having a lengthwise central slot, and a lateral suction opening, means protecting the slot 110 from contact with a paper machine screen, and means for mounting said box comprising hangers, bolts engaging the hangers, and the ends of the box, and spacing elements mounted in one of said connected parts and engag- 115 ing the other.

5. A suction box for paper making ma- 120 chines comprising a hollow tubular casing having a lengthwise central slot, and a lateral suction opening, means protecting the slot 125 from contact with a paper machine screen, and means for mounting said box comprising hangers, bolts engaging the hangers and the ends of the box, and spacing elements mounted in one of said connected parts and engag- 130 ing the other, the bolt engaging portion of the box comprising flanged bodies formed at the ends of the box, and lying below the plane of screen protecting member, 135

6. In a suction box for a Fourdrinier adjacent the bolts for securing the bolts in paper making machine or the like, a hollow casing with flanged upper portions; tongue members extending from the upper faces of the flanged portions, screen abutting means with cooperating grooves secured in the tongue members forming transverse suction apertures opening into the hollow casing and adjustable filler members closing the ends of the transverse apertures, for regulating the transverse suction area into the casing.
7. In a device of the character specified, a hollow metal casing, a flange and a plug at one end of the casing, a flange at the other end for connecting with a suction pipe, means for retaining wooden means removable from the casing, said members adapted to make an opening into the hollow casing and adjustable means of supporting said casing from side frame members of a paper making machine.
8. In a suction box for a Fourdrinier paper making machine or the like, a hollow casing with means for detachably securing to said casing a screen abutting member, and means for securing said box to the frame members of said machine, said means comprising bolts retained in the casing and the frame of the machine with adjustment screws
9. A suction box for paper making machines comprising a hollow casing having lateral flanges forming an integral top, said flanges leaving an opening between them, a suction connection at one end of the casing, and a removable closure for the other end of the casing to permit flushing, and means mounted on the box for protecting a screen passing over said opening, said means comprising a foraminated integral body, and dovetails on the casing flanges for slidably engaging the same, the apertures formed in the foraminated body of less area at the screen abutting side thereof than at the base.
10. In a device of the character specified, a hollow metal casing, a flange and a plug at one end of the casing, a flange at the other end for connecting with a suction pipe, means for retaining wooden means removable from the casing, said members adapted to make an opening into the hollow casing and adjustable means of supporting said casing from side frame members of a paper making machine, and slideable members at the ends of said integral piece for blanking off said apertures at the ends of said casing.

JOHN H. REEDY.
